UNITED STATES PATENT OFFICE

CLARENCE S. SNAVELY, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed April 8, 1927. Serial No. 181,987.

My invention relates to railway traffic controlling apparatus, and particularly to apparatus of the type comprising means for supplying the trackway with current which is periodically interrupted at different frequencies and governing means on the train selectively controlled in accordance with the frequency of such variations.

I will describe several forms of railway traffic controlling apparatus embodying my invention, and will then point out the novel features thereof in claims.

In the accompanying drawings, Fig. 1 is a diagrammatic view illustrating one form of railway traffic controlling apparatus embodying my invention. Fig. 2 is a view showing in vertical longitudinal section, a portion of the apparatus illustrated diagrammatically in Fig. 1 and also embodying my invention. Fig. 3 is a detail sectional view along the line III—III of Fig. 2. Fig. 4 is a diagrammatic view showing a modified form of a portion of the apparatus illustrated in Fig. 1 and also embodying my invention. Fig. 5 is a vertical longitudinal sectional view of the master controller H illustrated diagrammatically in Fig. 4 together with the circuit controller Q and the commutating device S operated thereby and all embodying my invention. Fig. 6 is a view showing in end elevation the devices illustrated in Fig. 5. Fig. 7 is a sectional view along the line VII—VII of Fig. 5. Fig. 8 is a view showing in vertical longitudinal section the motor T illustrated diagrammatically in Fig. 4. Fig. 9 is an end view of the motor T shown in Fig. 8 with certain of the parts broken away to show the construction. Fig. 10 is a diagrammatic view showing a modified form of apparatus embodying my invention. Fig. 11 is a view showing one modification of a part of the apparatus shown in Fig. 10 and also embodying my invention.

Similar reference characters refer to similar parts in each of the several views.

Referring first to Fig. 1, the reference characters 1 and 1^a designate the track rails of a stretch of railway track over which traffic normally moves in the direction indicated by the arrow. Train controlling cur-

rent is supplied to the rails of this stretch of track from a suitable source of energy which is here shown as an alternator G. The alternating current supplied to the trackway by the alternator G may be of any suitable frequency and for purposes of convenience the frequency of this current may be of the order of the usual commercial current, such for example, as 60 cycles or 100 cycles per second.

The supply of current to the trackway is controlled by a coding device designated in general by the reference character A. In the form here shown this coding device comprises a rotatable shaft 2 operatively connected with a constant speed motor M which receives energy from the alternator G. Rigidly attached to the shaft 2 are a plurality of code wheels each designated by the reference character E with a suitable distinguishing exponent and each of which may be of conducting material and may be provided at its periphery with alternately disposed insulating segments 3 and conducting teeth 4. Bearing on the periphery of each of the coding wheels E is a brush 5 which is connected to one of the fixed contacts of a circuit controller D which may be controlled in a suitable manner. In actual practice the circuit controller D will usually be operated in accordance with traffic conditions. One terminal of alternator G is connected directly with rail 1, and the other terminal of the alternator may be connected with rail 1^a through any selected one of the coding wheels E depending upon the position of the circuit controller D. It follows that the alternating current supplied to the trackway by alternator G is periodically interrupted at a frequency which corresponds to the number of teeth in the coding wheel E which is interposed between the alternator and the track rails. It will be noted that the several coding wheels E are provided with different numbers of conducting teeth 4. It follows that the alternating current supplied to the track rails is periodically interrupted at different frequencies depending upon which of the code wheels is included in the trackway circuit. The coding device A may be constructed to pro-

vide any reasonable number of coding frequencies but for purposes of illustration I have shown only three coding wheels. I will assume that the shaft 2 operates at 6 twenty revolutions per minute and that wheel E¹ has four conducting teeth, that wheel E² has six conducting teeth and that wheel E³ has nine teeth. It should be clearly understood that these particular values 10 are not essential but I have discovered that with the values stated there is a minimum of interference with the coded currents by stray energy from conductors which may be adjacent the trackway.

15 With the apparatus thus far described, when circuit controller D is in the position in which it is illustrated in the drawing, so that contact 6-7 is closed, the alternating current supplied to the trackway by alternator G, which current I will assume to be of 100 cycles per second, is interrupted at a frequency of 180 cycles per minute. Current supplied to the trackway under such 20 conditions I will hereinafter term the "proceed code". When contact 6-8 of circuit controller D is closed the trackway is supplied with 100 cycle current interrupted at a frequency of 120 cycles per minute and this code I will hereinafter term the "caution 25 code". In similar manner when contact 6-9 of circuit controller D is closed the trackway is supplied with 100-cycle current interrupted at a frequency of 80 cycles per minute, which current I will hereinafter 30 term the "slow code".

35 A train indicated diagrammatically at V is provided with governing means which is selectively responsive to the frequency of the periodic interruptions in the 100 cycle current supplied to the trackway. I prefer to accomplish this selective response by 40 taking advantage of the phenomenon of electrical resonance. Under some conditions it may be undesirable to use apparatus which 45 is electrically tuned directly to the code frequencies of the low order which I have suggested. I therefore provide on the train means for creating alternating currents of 50 frequencies higher than but proportional to the frequencies of the periodic interruptions in the trackway current. The train may then be provided with tuned circuits which 55 are separately responsive to these higher frequencies. In the present embodiment of my invention, I accomplish these results by providing the train with a receiver comprising two magnetizable cores 11 and 11^a located in advance of the forward axle 10 and disposed in inductive relation with the two 60 track rails 1 and 1^a respectively. Core 11 is provided with a winding 12, and core 11^a is provided with a similar winding 12^a, the two windings 12 and 12^a being connected in series in such manner that the voltages induced therein by train controlling current

flowing in the trackway are additive. Windings 12 and 12^a are connected through an amplifier 13 and a transformer 14 with a polarized relay R. When train controlling current is being supplied to the trackway, 70 pulsating energy is delivered to the primary of transformer 14 at the frequency of the periodic interruptions in such trackway current. For each impulse of energy supplied to transformer 14, during the increase of 75 such current, an impulse of one relative polarity is supplied to relay R, and during the decrease of such current, an impulse of the opposite relative polarity is supplied to the relay. The relay R is responsive to 80 the relative polarity of the current supplied thereto and it follows that when the train controlling current supplied to the trackway is being periodically interrupted, the relay R is operated to swing its armature 15 85 alternately to the right and left at a frequency which corresponds to the frequency of the interruptions in the trackway current.

Associated with relay R is a motor P 90 which is arranged to operate at a speed which depends upon the frequency at which relay R is operated. In the present embodiment of my invention the motor P comprises two stator windings 17 and 18 which are 95 supplied with current from a battery 16 over contacts controlled by relay R. The motor P also comprises a rotor winding 19 which is constantly supplied with current from battery 16. When relay R is energized 100 in one direction, current from battery 16 flows over contact 15-15^a of relay R to winding 17 of motor P, and when relay R is energized in the other direction current flows over its contact 15-15^b to winding 18 of 105 motor P.

Referring now also to Figs. 2 and 3, the motor P comprises a suitable housing 34 containing a stator 33 which carries the windings 17 and 18 wound in a manner similar to the usual induction motor. The motor also comprises a rotor 32 carrying winding 19, and mounted freely on a shaft 35 which is supported in suitable bearings in the housing 34. The rotor 32 is provided with a yoke 42 which receives one end of a leaf spring 43, the other end of which is rigidly attached to the housing 34. The rotor 34 is therefore biased to a definite position. The windings 17, 18 and 19 of the motor P are arranged in such manner that when current is supplied to winding 17 of the stator 33, the rotor 32 is moved in a clockwise direction, as seen from the right in Fig. 2, against the bias exerted by spring 43. When winding 18 is energized, however, the rotor is moved in the opposite direction.

Rigidly attached to the shaft 35 is a ratchet wheel 36 which co-operates with a pawl 37 pivoted on a post 38 attached to

the housing 34. As best shown in Fig. 3, the ratchet wheel 36 and pawl 37 permit rotation of the shaft 35 in a clockwise direction as viewed from the right in Fig. 2 but prevent motion of the shaft in the opposite direction. A ratchet wheel 39 similar to wheel 36 is rigidly attached to the shaft 35 and this ratchet wheel co-operates with a pawl 40 journalled on a pin 41 in the rotor 42. The pawl 40 and ratchet wheel 39 permit rotation of the rotor 42 in a counter clockwise direction about the shaft 35 as seen from the right in Fig. 2 but these members prevent relative motion of the rotor and the shaft in the opposite direction. When relay R is operating intermittently, the rotor 32 is moved a predetermined distance which is defined by the disposition of the motor windings, each time winding 17 is energized by the closing of contact 15-15^a of the relay. I will assume that this motion of the rotor is clockwise as viewed from the right in Fig. 2. During this motion of the rotor the pawl 40 engages the ratchet wheel 39 and rotates the shaft 35 in a clockwise direction as viewed from the right in Fig. 2. When the relay R next becomes energized in the opposite direction to close contact 15-15^b, the combined effect of the energization of winding 18 and the bias exerted by spring 43 returns the rotor to its initial position. During this motion of the rotor the pawl 37 engages the ratchet wheel 36 to prevent rotation of the shaft 35 and the pawl 40 rides past one or more teeth of the ratchet wheel 39 without moving the shaft. It is manifest, therefore, that when relay R is operating intermittently the rotor 42 of the motor P oscillates to and fro and that this oscillation of the rotor advances shaft 35 in one direction by a definite amount for each oscillation of the rotor. It follows that the shaft 35 of the motor P is rotated in a step-by-step fashion at a speed which is directly proportional to the frequency of the code which is being supplied to the trackway.

A rotatable shaft 46 is operatively connected with the shaft 35 through some suitable form of impulse absorbing apparatus. In the form here shown a spiral spring 44 has one end attached to the shaft 35 and has its other end attached to a drum 45 carried by the shaft 46. The step-by-step motion of the shaft 35, operating through the spring 44 causes substantially uniform rotation of the shaft 46. The shaft 46 carries a gear 47 which meshes with a pinion 48 on a spindle 100. A second gear 49 is rigidly attached to the spindle 100 and meshes with a pinion 50 attached to the shaft 51 of an alternator L. Due to the step-up gearing interposed between the shaft 46 and the shaft 51 of the alternator, the alternator is operated at a considerably higher speed than

the motor P. The alternator L is constructed in the usual manner and comprises a stator winding 20 which is constantly supplied with direct current from battery 16 as shown in Fig. 1. The alternator L also comprises a rotor winding 21 which delivers alternating current to the conductors 31 and 31^a through the usual slip rings and brushes. By properly adjusting the proportions of the step-up gearing between the shafts 46 and 51, and by suitable construction of the alternator L, the frequency of the current delivered to the conductors 31 and 31^a may be made considerably higher than the frequency of the code which is supplied to the trackway to operate the motor P. Of course the frequency of the current delivered by the alternator is directly proportional to the speed at which this shaft is driven and it follows that the frequency of the current supplied to the conductors 31 and 31^a is directly proportional to the frequency of the interruptions in the current supplied to the trackway. For purposes of explanation I will assume that when the trackway current is periodically interrupted at the rate of 180 cycles per minute in accordance with the proceed code, the frequency of the current delivered by the alternator is 180 cycles per second, but any other suitable ratio could be chosen for the relation between the code frequencies and the corresponding frequencies of the output of the alternator L.

Connected in parallel with the conductors 31 and 31^a are a plurality of tuned circuits each designated by the reference character F with an appropriate exponent and each supplying energy to a rectifier designated by the reference character J with a corresponding exponent. (See Fig. 1.) Each of the circuits F includes a reactor 27 and a condenser 26, and the several circuits are each tuned to resonance at the several frequencies of the current supplied by the alternator L. Thus, the circuit F³ is tuned to resonance at 180 cycles per second, circuit F² at 120 cycles per second and circuit F¹ at 80 cycles per second. Each of the rectifiers J has its output terminals connected with a relay designated by the reference character K with a suitable distinguishing exponent. The parts are so adjusted and proportioned that each relay K is energized when the current delivered by the alternator L is of the frequency at which the associated circuit F is tuned to resonance but that the relay is de-energized under all other conditions.

In explaining the operation of the apparatus as a whole, I will first assume that contact 6-7 of circuit controller D is closed so that current is supplied to the trackway in accordance with the proceed code. Under these conditions the relay R is operated at a frequency of 180 cycles per minute. The motor P therefore drives alternator L at 180

such a speed that the current delivered by the alternator is of 180 cycles per second. Current of this frequency energizes relay K^1 and K^3 but at this frequency the circuits F^1 and F^2 are detuned so that relays K^1 and K^2 are de-energized. Current from battery 16 therefore flows over front contact 28-28^a of relay K^3 to a lamp 22, which lamp therefore becomes lighted to indicate proceed. When contact 6-8 of circuit controller D is closed to supply current to the trackway in accordance with the caution code the relay R operates at a frequency of 120 cycles per minute and under these conditions the current delivered by alternator L has a frequency of 120 cycles per second. Relay K^2 is therefore energized but relays K^1 and K^3 are open so that current flows from battery 16 over back contact 28-28^b of relay K^3 and front contact 29-29^a of relay K^2 to lamp 23, thereby lighting this lamp to indicate caution. In similar manner when the slow code is being supplied to the trackway, current of 80 cycles per second is delivered by the alternator L and under these conditions relay K^1 is energized and relays K^2 and K^3 are de-energized. Lamp 24 is, therefore lighted to give a slow indication by current which flows from battery 16 over back contact 28-28^b of relay K^3 , back contact 29-29^b of relay K^2 , and front contact 30-30^a of relay K^1 to lamp 24.

It should be pointed out that should the supply of alternating current to the track rails be discontinued, or should alternating current be supplied without interruption to the trackway, or if for any other reason the alternator L should fail to operate, no current would be supplied to the tuned circuits F and the relays K would all be de-energized. In this case current from battery 16 would flow over back contact 28-28^b of relay K^3 , back contact 29-29^b of relay K^2 and back contact 30-30^b of relay K^1 to lamp 25, thereby lighting this lamp to indicate stop.

Referring now to Fig. 4, I have here shown a modified form of apparatus for operating the alternator L at different speeds which are proportional to the frequency of operation of relay R. In the modification here shown the contacts of relay R operate a master controller designated by the reference character H which drives a circuit controller Q and operates a commutating device designated in general by the reference character S. This commutating device controls the supply of current to a motor T which is operatively connected with the alternator L. The alternator L supplies current to a plurality of tuned circuits in exactly the same manner as in Fig. 1.

Referring now also to Figs. 5, 6, and 7, the master controller H comprises a plurality of electromagnets disposed circumferen-

tially about a rotatable shaft 65 carrying two armatures 66 and 67 having a substantially Z-shaped configuration. As here shown the master controller comprises eight electromagnets of which each two diametrically opposite magnets are connected in series. This is best shown in Fig. 4, from which it will be seen that the windings of magnets 58 and 58^a are connected in series, and that the windings of the remaining pairs of magnets 59 and 59^a, 60 and 60^a, 61 and 61^a, are also connected in series. As shown in Figs. 4, 5 and 6, each of the magnets comprises a core 62 which carries the magnet winding and which is provided at its extremity with two radially extending pole pieces 63 and 64. The armature 66 is in the plane defined by the pole piece 63, and the armature 67 is in the plane defined by the pole piece 64. Furthermore the two armatures, which are rigidly attached to the shaft 65 are so disposed that when one armature 66 is aligned with the pole piece 63 of one pair of magnets the other armature 67 is also aligned with the pole piece 64 of the same pair of magnets. Due to the Z-shape of the armature, it will be plain that when one pair of magnets is energized, the armatures will be moved to a position in which the air gaps between the pole pieces of this pair of magnets and the armatures have their minimum lengths. For example, referring to Fig. 4, if magnets 58 and 58^a are energized, the armatures will assume the positions in which they are illustrated in the drawing. If now magnets 61 and 61^a become energized the armatures will be rotated in a clockwise direction through an angle of 45 degrees and the armatures will then bear the same relation to the pole pieces of magnets 61 and 61^a as the armatures bear to the pole pieces of magnets 58 and 58^a as shown in the drawing.

A circuit controller designated in general by the reference character Q is operated by the shaft 65, and in the form here shown, this circuit controller comprises a rotatable disk 70 of insulating material rigidly attached to the shaft 65. This disk is provided with a contact strip which covers portions of the periphery of the disk so that the edge of the disk is provided with two conducting segments 70^b separated by insulating segments 70^a. Bearing upon the edge of the disk 70 are four brushes 71, 72, 73 and 74, which are supported by, but insulated from the frame of the master controller H. (See Figs. 5 and 6.) These brushes are so disposed about the periphery of the disk that for any position of the disk 70, two and only two of the brushes bear against the conducting segments 70^b of the disk. The segments 70^b are integral portions of the same contact member so that these segments are electrically connected together. These seg-

ments are connected by means which will be explained in detail hereinafter with one terminal C of a suitable source of energy not shown in the drawing. This electrical connection is illustrated diagrammatically in Fig. 4 by wire 126.

In explaining the operation of the master controller, I will first assume that the parts of the apparatus occupy the positions in which they are illustrated in Fig. 4. Under these conditions, relay R is energized to close contact 15-15^a and the armatures of the master controller are aligned with magnets 58 and 58^a as has already been explained. With the parts in these positions, brushes 72 and 73 engage a conducting segment 70^b on the disk 70. Current, therefore flows from terminal B of the energy source, through contact 15-15^a of relay R, magnets 58 and 58^a, brush 73, conducting segment 70^b and back to terminal C of the same source. The armatures on the shaft 65 are, therefore held in a position in which they are aligned with the pole pieces of magnets 58 and 58^a. When relay R next becomes energized to close contact 15-15^b, current flows from terminal B, through contact 15-15^b of relay R, magnets 61 and 61^a, brush 72, conducting segment 70^b and back to terminal C. Magnets 61 and 61^a are, therefore energized and the circuit just traced for magnets 58 and 58^a is interrupted so that the armatures 66 and 67 are swung into alignment with magnets 61 and 61^a, thereby rotating the shaft 65 in a clockwise direction as seen in Fig. 4 through an angle of 45 degrees. This motion of the shaft 65 rotates the disk 70 into a position in which brushes 71 and 72 engage a conducting segment 70^b and brushes 73 and 74 engage an insulated portion of the disk 70. When relay R next becomes reversed current flows from terminal B, through contact 15-15^a, magnets 60 and 60^a, brush 71, and thence to terminal C, thereby moving the shaft 65 through a further angle of 45 degrees into a position in which the armatures 66 and 67 are aligned with magnets 60 and 60^a. It will be plain from the foregoing that when relay R is operated intermittently, the joint control of the energization of the magnets of the master controller H by the contacts of this relay and by the circuit controller Q results in a step-by-step motion of the armatures 66 and 67 which drives the shaft 65 in a clockwise direction as seen in Fig. 4. The shaft is advanced a distance of 45 degrees for each reversal of the relay, and it follows that the speed of rotation of the shaft is directly proportional to the frequency at which the relay R operates and is, therefore directly proportional to the frequency at which the trackway current is periodically interrupted.

The shaft 65 also operates a commutating device designated in general by the refer-

ence character S and comprising a commutator proper 68 and two brushes 78 and 84 bearing upon the periphery of this commutator. Referring particularly to Figs. 5 and 7, the commutator 68 comprises a plurality of insulated contact bars 69 and this commutator is rigidly attached to the frame of the master controller H. The disk 70 of the circuit controller Q carries two inwardly projecting posts 75 and 81, one of which, 75 75, is electrically connected with the conducting segments 70^b of the circuit controller Q. The post 75 carries a brush 77 which bears against the inner surface of a collecting ring 79 which is constantly connected with terminal C of the energy source. It is by means of this arrangement that the conducting segments of the circuit controller Q are connected with the source of energy which supplies current to the magnets 85 of the master controller. The post 75 also carries a brush 78 which bears upon the periphery of the commutator 68. The post 81 is also mounted upon the disk 70 but this post is insulated from the conducting segments of the circuit controller and carries the brush 84 which bears upon the commutator 68 and a second brush 83 which constantly engages the inner surface of a second collecting ring 80 carried by the frame 90 of the master controller, and connected with terminal B of the energy source. It will be plain that as the shaft 65 of the master controller is rotated due to the intermittent operation of the relay R, the brushes 78 100 and 84 carried by the disk 70 are moved around the periphery of the fixed commutator 68. But the collector ring 80 is constantly connected with the terminal B of the energy source and collector ring 79 is constantly connected with terminal C of the same source. The several bars 69 of the commutators are, therefore successively connected with the respective terminals of the energy source as the shaft 65 of the master 110 controller is rotated.

The commutating device S controls a motor designated in general by the reference character T (Fig. 4) and illustrated in detail in Figs. 8 and 9. This motor comprises a stator provided with a winding 88 which is constructed in a manner similar to the armature winding of the usual direct current motor. This winding is connected at intervals with leads which are connected 115 respectively with a plurality of screws 105 mounted upon a suitable terminal board 106. Each bar 69 of commutator 68 is connected with one of the terminal screws 105 on the terminal board 106 of the motor T 120 by a lead 85 only a few of which are shown in Fig. 4. It follows that when the master controller H is operated to rotate the brushes 78 and 84 about the surface of the fixed commutator 68, there is created in the wind- 130

ing 88 of the motor T a rotating magnetic field, the speed of rotation of which is directly proportional to the speed of rotation of the master controller H.

5 The motor T also comprises a shaft 89 carrying a field structure 87 provided with a rotor winding 150 to which direct current is constantly supplied from terminals B and C of the energy source through binding posts 94 and 95 which carry brushes 92 and 93, respectively. (See Fig. 8.) Brush 93 engages a slip ring 91, and brush 92 engages a slip ring 101. The two slip rings 91 and 101 are connected with the terminals 15 of the rotor winding 150 in the usual manner. The motor T, therefore operates as an inverted direct current motor, that is, the usual fixed pole structure of the direct current motor is here mounted upon the 20 shaft 89 to rotate in accordance with the rotating field caused by the winding 88 which is analogous to the usual armature winding of the direct current motors well known in the art. The shaft of the motor, 25 therefore rotates at a speed which is directly proportional to the speed of rotation of the master controller H, and is, therefore directly proportional to the frequency of operation of the relay R.

30 Attached to the shaft 89 of the motor T is an arm 96 carrying a stud 97 to which is attached one end of a spiral spring 98. The other end of the spring 98 is attached to the gear 47 which drives alternator L as in Fig. 2. The radial position of the stud 97 with respect to the arm 96 may be adjusted to provide different tensions of the spring 98 to absorb the impulses delivered to the shaft 89 and to deliver a substantially uniform turning torque to the gear 47.

35 It will be apparent from the foregoing explanation that when the trackway current is periodically interrupted to operate relay R intermittently, the master controller H operates to rotate shaft 65 at a speed which is directly proportional to the frequency of the interruptions of the trackway current. The 40 commutating device S is of course operated at the same speed as the shaft of the master controller, and motor T also operates at a speed which is proportional to the frequency of the interruptions in the trackway current. The frequency of the output current of alternator L is, therefore directly proportional 45 to, but may be considerably higher than, the code frequency, and the alternator may control governing means which is selectively responsive to the frequency of the current delivered thereto in the same manner as in

50 Fig. 1.

55 Fig. 10 illustrates a modified form of apparatus for creating alternating currents of comparatively high frequencies which are proportional to the comparatively low frequencies at which the trackway current is

interrupted to form the various codes. In this modification a shaft 110 is rotated at a speed which is proportional to the frequency of the periodic interruptions in the trackway current. For example, as shown in the 70 drawing, the shaft 110 is operatively connected with the rotatable armature 19 of a motor P similar to the motor P in Fig. 1. It will, therefore be plain that shaft 110 is operated by the motor P at a speed which is proportional to the frequency of the periodic interruptions in the trackway current.

75 Rigidly attached to the shaft 110 is a cam 111 provided at its periphery with a comparatively large number of swells 112 separated by notches 113. Operated by cam 111 is a movable contact lever 114 provided with an insulating cam follower 115 co-operating with the edge of the cam. The lever 114 operates with two fixed contacts 114^a and 114^b in such manner that as the cam 111 rotates and the follower 115 alternately engages the swells 112 and the notches 113 in the cam, the lever 114 is swung into engagement with contacts 114^a and 114^b alternately. The contacts 114—114^a and 114—114^b in parallel are connected in series with the primary 116 of a transformer X which is supplied with direct current from a suitable source such as battery 16. It follows 90 that when the cam 111 is rotated the current in the primary 116 of transformer X is periodically interrupted twice for each swell 112 of the cam 111 which engages the cam follower 115. The periodically interrupted current thus supplied to the primary 116 of transformer X creates in the secondary of this transformer an alternating electromotive force which causes current to flow in the tuned circuits F¹, F² and F³. The alter-

95 nating current flowing in these tuned circuits is changed into direct current by the rectifiers J¹, J² and J³, respectively and 100 operates the relays K¹, K² and K³ in accordance with the frequency of such current in the same manner as in Fig. 1. It follows, therefore that periodic interruptions of the trackway current of comparatively low frequencies are "stepped up" to alternating currents of comparatively high frequencies in 105 the secondary of transformer X and that the relays K¹, K² and K³ are selectively responsive to these comparatively high frequencies.

110 In Fig. 11, the contacts 114—114^a and 114—114^b are replaced by a variable impedance device designated in general by the reference character W and comprising a magnetizable core 118 having an air gap in which is located a rotatable member 120 of magnetizable material rigidly attached to 115 the shaft 110 driven by the motor P. The member 120 is provided with alternate poles 121 and notches 122 so that when the member 120 rotates, the reluctance of the magnetic path through the core 118 and the mem- 120

125 ber 120 rotates, the reluctance of the magnetic path through the core 118 and the mem-

ber 120 is periodically varied a plurality of times for each complete revolution of the shaft 110. The core 118 is provided with a winding 119 which is connected in series with the primary 116 of transformer X and the battery 16. When the shaft 110 is rotated, the current in the primary 116 of transformer X is periodically varied at a frequency which is higher than, but proportional to, the speed of rotation of the shaft 110. The secondary 117 of transformer X supplies current to the tuned circuits F¹, F² and F³ in the same manner as in Fig. 10.

It will be plain from the foregoing that with the apparatus shown in Fig. 11 the frequency of the current supplied by secondary 17 of transformer X is higher than, but proportional to, the frequency of the periodic interruptions of the trackway current.

In Figs. 10 and 11 the shaft 110 is operated by a motor P which in turn is controlled by a relay which is operated intermittently at a frequency corresponding to the frequency of the periodic interruptions in the trackway current, but this particular arrangement is not essential, the important feature being that the shaft 110 is rotated at a speed which is proportional to such interruptions.

It will be apparent, therefore, that my invention provides apparatus by means of which alternating currents of commercial frequencies supplied to the trackway may be periodically interrupted at comparatively low frequencies of the order from 1 to 3 cycles per second and that these comparatively low frequencies control apparatus on board the train which creates alternating currents of frequencies which are higher than, but proportional to, the frequencies of the periodic interruptions of the trackway current. In systems embodying my invention, therefore, I combine the advantages which result from the use of low frequencies for the various codes, such as freedom from interference, with the advantages inherent to tuning to comparatively high frequencies for selection between the frequencies.

In each of the forms of apparatus which I have disclosed, the control of the train carried governing means is effected through the medium of a relay R which is intermittently operated in accordance with the interruptions in the trackway current, but this particular arrangement is unnecessary. Furthermore it should be pointed out that although I have illustrated two specific arrangements of apparatus for operating the alternator L at speeds which are proportional to the speed of the interruptions in the trackway current, any other suitable arrangement of apparatus may be substituted for the mechanism which I have disclosed.

Although I have herein shown and described only a few forms of railway traffic

controlling apparatus embodying my invention, it is understood that various changes and modifications may be made therein within the scope of the appended claims without departing from the spirit and scope of my invention.

Having thus described my invention, what I claim is:

1. In combination, a source of current, means for periodically interrupting such current, means responsive to such interruptions for creating an alternating current the frequency of which is different from, but proportional to, the frequency of such interruptions, and means selectively responsive to the frequency of such alternating current.

2. In combination, a source of current, means for periodically interrupting such current at different low frequencies means responsive to such interruptions for creating alternating currents the frequencies of which are higher than, but proportional to, the frequencies of such interruptions, and means selectively responsive to the frequencies of such alternating currents.

3. In combination, a source of current, means for periodically interrupting such current, a motor device responsive to such interruptions, but not to the current itself, an alternator operatively connected with the motor device, and means receiving alternating current from the alternator and selectively responsive to the frequency of the received current.

4. In combination, a source of alternating current, means for periodically interrupting such current, a motor responsive to the interruptions in said current but not to the current itself, an alternator operated by the motor, and governing means controlled by the alternator.

5. Railway traffic controlling apparatus comprising means for supplying alternating current to the trackway, means for periodically interrupting such alternating current at different frequencies, a train carried motor receiving energy from the trackway and operating at a speed which is proportional to the frequency of such interruptions, an alternator operated by the motor, and governing means selectively responsive to the frequency of the current delivered by the alternator.

6. Railway traffic controlling apparatus comprising means for supplying current to the trackway, means for periodically interrupting such current at different frequencies, means responsive to such interruptions for creating on a train alternating currents the frequencies of which are different from, but proportional to, the frequencies of such interruptions, and governing means on the train selectively responsive to the frequencies of such alternating currents.

7. Railway traffic controlling apparatus

- comprising a train carried motor, means located partly in the trackway for operating the motor at different speeds, an alternator operatively connected with the motor, and governing means selectively responsive to the frequency of the current delivered by the alternator.
8. Railway traffic controlling apparatus comprising means for supplying alternating current to the trackway, means for periodically interrupting such alternating current, a train carried motor responsive to the interruptions in such current but not to the current itself, an alternator operated by the motor, a relay receiving energy from the alternator, and a tuned circuit interposed between the alternator and the relay.
9. Railway traffic controlling apparatus comprising means for supplying alternating current to the trackway, means for periodically interrupting such alternating current at different frequencies, a train carried motor receiving energy from the trackway and operating at a speed which is proportional to the frequency of such interruptions, an alternator operated by the motor, a plurality of relays receiving energy from the alternator, and a plurality of tuned circuits one interposed between each relay and the alternator.
10. Railway traffic controlling apparatus comprising a train carried relay, means located partly in the trackway for operating the relay intermittently at different frequencies, an impulse motor, means for operating the motor at a speed which is proportional to the frequency of operation of the relay, an alternator operated by the motor, and governing means selectively responsive to the frequency of the current delivered by the alternator.
11. In combination, an impulse motor comprising a rotor biased to an initial position, means for periodically moving the rotor away from its initial position at different frequencies, a shaft rotated in a single direction at a speed which is proportional to the frequency of oscillation of the rotor, an alternator operated by the shaft, and a plurality of devices selectively responsive to the frequency of the current supplied by the alternator.
12. In combination, an impulse motor comprising a rotor, means for oscillating the rotor through a small angle at different frequencies, a rotatable shaft, means for advancing the shaft a predetermined distance in one direction for each oscillation of the rotor, an alternator operated by the shaft, and a plurality of relays selectively responsive to the frequency of the current supplied by the alternator.
13. Railway traffic controlling apparatus comprising a train carried motor, means located partly in the trackway for operating the motor at different speeds, an alternator driven by the motor, a plurality of relays receiving energy from the alternator, and resonant means interposed between each relay and the alternator and each tuned to a different frequency.
14. In combination, a stretch of railway track supplied with alternating current, means for periodically interrupting such current at different frequencies, a train carried relay responding to the interruptions in such current but not to the current itself, a motor controlled by the relay, an alternator controlled by the motor, a plurality of resonant circuits all connected in parallel with the alternator and each tuned to resonance at a different frequency, and a plurality of relays one receiving energy from each said circuit.
15. Railway traffic controlling apparatus comprising a train carried motor having a fixed winding and a movable winding, means for supplying direct current to one of said windings, means located partly in the trackway for supplying periodic current to the other winding whereby the movable winding oscillates at the frequency of such periodic current, an alternator, means responsive to the oscillations of the movable winding of the motor to drive the alternator in one direction, and a tuned circuit receiving energy from the alternator.

In testimony whereof I affix my signature.
CLARENCE S. SNAVELY.
